BAG CLOSING MACHINE

Robert N. Cundall, Lackawanna, and Lincoln A. Cundall, Buffalo, N. Y., assignors to Bagpak, Inc., a corporation of Delaware

Application December 17, 1934, Serial No. 757,772

2 Claims. (Cl. 112—11)

Our present invention relates to a machine for sewing and sealing the mouths of filled bags, particularly large multiply bags made of heavy paper material. This machine is designed primarily for use in plants, the output of which is fairly limited quantities of various sizes of bags. For such industries it is apparent that a relatively slow machine, operated by a single workman, and having a wide range of practically instantaneous 10 adjustability is desired. The principal object of our present invention is to devise such a machine.

Another object of our invention is to devise such a machine in which rigidity is obtained without sacrificing lightness and mobility, and which is 15 simply and inexpensively operated.

Our invention comprises an improvement upon the machine set forth in our copending application Serial No. 680,538, filed July 15, 1933. The improvements comprising our present invention 20 will be apparent from the following detailed description.

Referring to the drawings wherein like numerals refer to like parts throughout:

Fig. 1 is a front elevation of the machine;

Fig. 2 is a top plan view on an enlarged scale of the essential portions of the machine;

Fig. 3 is an end elevation looking at the right end of Fig. 1;

Fig. 4 is a section in plan taken along line 4—4 30 of Fig. 1;

Fig. 5 is a vertical section taken along line 5—5 of Fig. 1; and

Fig. 6 is a vertical section taken along line 6—6 of Fig. 1.

The machine comprises an endless belt conveyor designated as a whole by the letter A; a bag sewing mechanism designated as a whole by the letter B; and a bag sealing mechanism designated as a whole by the letter C. The sewing and sealing mechanisms are supported on standards above the conveyor in order that bags placed thereon may be guided through the machine and properly closed.

The conveying mechanism A comprises an endless belt 10 supported by rollers 11 mounted in a frame 12. At the ends of the frame 12 there are end rolls 13 and 14 about which the belt passes. Mounted below the frame are supporting rolls 15 to support the lower lap of the belt. End rolls 13 and 14 are mounted upon extensions of the frame 12 and adjusting devices 16 enable the rolls to be adjusted longitudinally of the frame in order that the belt may be aligned and tightened. End roll 13 is mounted upon a drive shaft 17 which is rotated by a sprocket and associated sprocket chain 18 driven by a sprocket on a shaft mounted in bearing 19. The latter shaft is driven by a sprocket chain 20 from a shaft associated with a clutch 21. This clutch is connected 60 through a reducing gear box 22 and a belt 23 to

a motor 24. The clutch 21 is engaged and disengaged in the usual manner by means of a link 25 connected through a bell crank 26 to a link 27 and a rocker arm 28 mounted upon and rocked by a rod 29. Rod 29 is pivotally mounted in the framework of the machine and is partially rotated by levers 30, 31 carrying a foot-bar 32. Upon depression of the foot-bar 32 by the operator, who is standing in front of the machine, the clutch 21 will be engaged and the conveyor 10 belt 10 will be caused to convey a filled bag placed thereon through the machine.

The mechanism for sewing through the mouth of the bag comprises a suitable sewing head 35 supplied with a thread or threads from spools 36 13 and which is preferably supplied with a reinforcing cord from a spool of cord 37. A second spool of reinforcing cord may be supplied, if desired, to reinforce the opposite side of the line of stitching. The reinforcing cord or cords are 20 passed beneath the loops of the stitching thread to prevent the stitches from tearing through the mouth of the bag. The details of the construction of the sewing machine are not essential to our invention and other types of machines than 25 that shown may be employed, if desired.

The sewing head 35 is mounted upon a bracket 40 which is adjustably fixed upon an upright T-beam 41, the arms of the T being toward the front. Near the top of bracket 40 there is formed 30 a sliding guide 42 and at the bottom of bracket 40 there is formed a vise-clamp 43. The guide 42 never binds against the arms of the T-beam but the clamp 43 may be loosened to allow vertical adjustment of the sewing head and tightened to 35 clamp the head in adjusted position. Mounted in the bracket 40 is a pinion gear 44 which meshes with a rack 45 on the T-beam. The pinion is rotated by a handwheel 46 to raise or lower the sewing head during such time as the clamp 43 40 is loosened. A chain 47 is fixed to the bracket 40 and passes around guide rolls 48, mounted upon the top of a T-beam 41, to a weight 49. The weight is formed in the shape of a saddle and is guided by the leg of the T-beam which 45 serves to keep it in alignment. The weight 49 counterbalances the weight of the sewing head and associated mechanism so that little effort is required to raise or lower the same.

The sewing mechanism is preferably operated 50 by means of a pulley 50 driven by a belt 51 from a pulley 52. Pulley 52 is loosely mounted upon a rod 53 fixed in an extension of bracket 40. Also loosely mounted upon rod 53 is a driving pulley 54, driven by a belt 55 and motor 56. The adjacent faces of pulleys 52 and 54 are roughened or provided with friction material so that when the pulleys are forced together the sewing machine will be driven. A spring may be mounted between the two pulleys to normally separate them 60

or elsewhere as is the usual fashion in such devices. Fixed to rod 53 is a cam member 57, with which is matched a cam member 58 adapted to be partially rotated by an arm and linkage to be further described. As cam member 58 is rotated with respect to member 57 pulley 54 will be moved to the left in Fig. 6 into driving engagement with pulley 52. Roller thrust bearings 59 and 60 adjust the hubs of pulleys 54 and 52 prevent undue friction.

Cam member 58 is partially rotated by a lever 65 which is operated by a link 66, connected with a lever 67 rocked by a shaft 68 mounted in bracket 40. Shaft 68 is rocked by a crank arm which is connected to a vertical rod 69 extending through guide openings in a bracket 70 mounted upon T-beam 41. Rod 69 also passes through an opening in a dog 71 which is pivotally connected to the upper end of a rod 72. The opening in the dog 71 is larger than the rod 69 so that it may be canted from its normal position for some distance before the edges of the opening will bind upon rod 69 and move that rod in conjunction with rod 72. A spring 73 interposed between dog 20 71 and the lower arm of bracket 70 tends to maintain dog 71 in the normal or loose position so that rod 69 will freely slide through dog 71 in either direction as the sewing head is vertically adjusted. Fixed to the rod 29, which is rocked by the 30 foot-bar 32, as previously described, is a crank arm 74 connected to a link 75 which rocks a crank 76, rod 77 and crank 78 connected to rod 72. As foot-bar 32 is depressed a sufficient distance the sewing machine will be operated as explained 35 below.

The foot-bar 32, upon its being depressed, will first engage the clutch 21 to start the conveyor 10 in order that the bag may be brought from the extreme loading end of the machine adjacent 40 guide roll 14 to a position adjacent the sewing head. As the bag approaches the sewing head the operator will position its mouth against a guide 80 having a lip 81 thereon which aligns the bag mouth with respect to the sewing needle. 45 The guide 80 is fixed to the sewing head 35. At about the time that the bag mouth is being inserted into the channel formed by the lip 81 the sewing machine should be started. The initial depression of the foot-bar merely starts the conveyor since the movement imparted to rod 72 is just enough to cant dog 71 without causing vertical movement of rod 69. Upon complete depression of foot-bar 32 at the instant desired the dog 71 binds against and moves rod 69 to cause 50 engagement of the pulleys 52 and 54. Likewise, it will be apparent that by releasing the foot treadle a slight distance after the bag mouth has been sewed the bag may be caused to travel onward into the sealing mechanism while the sewing machine stops, there being no necessity for loss of time between operations. The sewing machine is preferably provided with a well known type of shears which severs the stitches and reinforcing cord at the rear of the bag before the 55 sewing machine is stopped, in order that excess wastage of sewing thread and reinforcing cords may be avoided.

The bag is now travelling onward into the sealing mechanism, which will be described. In Fig. 70 2 it is seen that the short shaft in bearing 19, which drives the conveyor sprocket chain 18 carries a bevel gear 85 which meshes with a bevel gear on a vertical shaft 86. Parallel to shaft 86 are posts 87 mounted upon the frame of the machine and joined at their upper extremities by

a framework 88. A frame of light beams 89 is supported in the space between posts 87 and guided thereby for free vertical movement by means of pairs of flanged rollers 90, each pair of which rolls freely upon one of posts 87. The vertical shaft 86 is supplied with a long keyway 91 and a sprocket gear 92 is keyed to the shaft 86 in such a manner that the gear is rotated by the shaft but free to move longitudinally thereof. The length of the keyway 91 allows considerable movement of this sprocket gear 92. A sprocket chain 93, driven by sprocket gear 92, drives a gear on an upright shaft 94 carried by the frame 89. Shaft 94 carries a sprocket gear driving a feed chain 95, a large gear meshing with a gear upon an opposed shaft 96 which drives the opposed feed chain 97 and a sprocket gear 98 which drives a sprocket chain 99 leading to the tape squeezing or pressing rolls and associated mechanism. Figs. 1 and 4 show how the preliminary tape 20 pressing rolls 100 and the two sets of secondary tape pressing rolls 101 are driven by associated gears and sprocket chains to rotate in unison. A sprocket gear mounted upon the shaft of one of rolls 100 drives a sprocket gear 102 which operates a shearing mechanism 103 to shear the sealing tape between bags, as will presently appear. The sealing mechanism described hereinabove and illustrated in Figs. 1 and 4 is more particularly described and claimed in detail in applicants' copending application, Serial No. 666,114, filed April 14, 1933, to which reference may be made for a clearer illustration thereof. The shearing mechanism is more fully illustrated and described in the copending application of Lincoln A. Cundall, Serial No. 11,563, filed March 18, 1935, to which reference may be made for a more complete illustration and description thereof.

Mounted above the frame 88 is a roll of tape 40 105 from which the tape 106 is led through an adhesive applier comprising an applying roll 107 mounted in a tank 108. The tape is then led around a guide roll 109 and into a former 110 wherein it is bent into inverted U-shape over the 45 mouth of the bag to cover the line of stitches and seal the bag against the escape of dust and the ingress of moisture, or other foreign substances. The tape 106 normally projects forward of the former 110 between the rolls 100 to 50 55 the shears 103, having been clipped from the last sealed bag. The rolls 100 are spring pressed but restrained from meeting to such an extent that they will not draw the tape even though revolving unless a bag is presented between the rolls. In this manner tape is not wasted and is held in readiness for the succeeding bag. Rolls 101 are spring pressed and serve to press the tape into firm adherence with the mouth of the bag. Rolls 100 and 101 are preferably provided 60 with annular grooves so situated as to allow passage of the ridge caused by the reinforcing cords. For further details of the tape applying mechanism and the rolls reference may be made to the aforementioned copending applications 65 Serial No. 680,538, filed July 15, 1933, and Serial No. 666,114, filed April 14, 1933. The shear 103 may be of any type, such as described in the aforesaid application Serial Nos. 680,538 and 666,114.

The portion of the bag sealing mechanism with which this application is particularly concerned comprises the mounting and arrangement of said mechanism. The frame 89 carrying the rolls, the shear, the former, and the adhesive applier, 70 75

is mounted for vertical movement upon the posts 87 and may be raised or lowered by means of the following mechanism. At the front of frame 88 there is a crank handle 115 by means of which 5 a shaft 116 carrying a worm 117 may be rotated. Worm 117 drives a worm gear 118 fixed to a shaft 119 carrying sprocket gears about which are passed sprocket chains 120, one of chains 120 being fixed to the right rear portion of frame 10 89, and the other being fixed to the left rear portion of frame 89. The opposite ends of chains 120 pass around guiding sprockets 121 carried by a loosely mounted shaft 122 at the rear of frame 88 and are attached to weights 123 which 15 counterbalance the weight of the frame 89 and its associated mechanism. Also attached to the weights 123 are sprocket chains 124 which pass around guide sprockets on shaft 122 and sprockets 125 carried by a loosely mounted shaft 20 126 at the front of frame 88 and are attached to the forward portion of frame 89. It is thus seen that by rotating crank 115 in either direction the four corners of the frame 89 may be uniformly raised or lowered as illustrated in Fig. 5, 25 in order that various sizes of bags must be sealed. The well known action of a worm and worm gear such as 117, 118 enables the frame 89 to be locked in any position that the crank 115 is rotated to obtain. It is apparent that an instantaneous adjustment of the sealing mechanism is 30 available to vertically shift said mechanism with respect to the lip of the bag or the line of stitches as well as to compensate for various heights of bags. Taken in connection with the adjustment of the sewing head 35 the machine as a whole is readily adaptable for packaging any commodity.

It will be seen that the shaft 86 is continuously driven by motor 24 during such time that the 40 conveyor 10 is operating alone, or whenever the sewing machine is operating in conjunction with the conveyor 10. However, no tape will be fed through the machine until a bag has been presented to the grip of rolls 100, the increased bulk 45 presented thereby causing the sticky tape to be pressed onto the bag mouth and fed forward with the bag until it is clipped by shears 103.

T-beam 41, posts 87 and shaft 86 are mounted upon a carriage frame 130 made up of larger 50 beams than those in the frames heretofore mentioned. In this manner it will be apparent that the sewing mechanism, while rigidly fixed with respect to the center line of the sealing mechanism, and which can be rigidly fixed vertically 55 with respect to the sealing mechanism, is nevertheless separated from the sealing mechanism except through the rigid frame 130. In this manner vibrations of the sewing machine motor 56 and of motor 24 are prevented from passing directly to the sealing mechanism, which vibrations were heretofore found to be of some annoyance. The frame 12 of the conveyor 10 is likewise adjustably mounted upon posts rising from the frame 130. Frame 130 is preferably provided 60 with wheels 131 to enable the machine to be moved rapidly from one position to another. A belt tightener 132 may be provided to keep chain 18 taut regardless of the adjustment of end roll 13.

Having described the preferred embodiment of 70 our invention we wish it to be understood that we

are not limited to the specific details since substitutions and alterations may be made therein which come within the scope of our invention as expressed by the following claims:

We claim:

1. In a bag closing and sealing machine having closing mechanism for closing the collapsed mouths of filled bags, sealing mechanism for adhering a strip of sealing material around the closed mouths and a conveyor for presenting the bags in succession to said mechanisms; a common control therefor comprising a foot-bar, a shaft connected to and rocked by said foot-bar, a common motor for driving said sealing mechanism and said conveyor, a clutch for connecting 10 said motor to said sealing mechanism and said conveyor for simultaneous operation, a second motor for driving said closing mechanism, a second clutch for connecting said closing mechanism to said second motor, a linkage extending 15 from said shaft to said first clutch to cause engagement thereof upon partial depression of said foot-bar, and a second linkage including a lost motion connection extending from said shaft to said second clutch to cause engagement thereof 20 upon continued depression of said foot-bar, said lost motion connection permitting engagement of said first clutch without engagement of said second clutch whereby said conveyor may operate simultaneously with said sealing mechanism 25 alone or simultaneously with both of said mechanisms.

2. In a bag closing and sealing machine having closing mechanism for closing the collapsed mouths of filled bags, sealing mechanism for adhering a strip of sealing material around the closed mouths and a conveyor for presenting the bags in succession to said mechanism; a common control therefor comprising a foot-bar, a shaft connected to and rocked by said foot-bar, 30 a common motor for driving said sealing mechanism and said conveyor, a clutch for connecting said motor to said sealing mechanism and said conveyor for simultaneous operation, a vertical shaft operated through said clutch and having a 35 sliding gear thereon through which said sealing mechanism is driven whereby the sealing mechanism may be vertically shifted with respect to said conveyor, a second motor for driving said closing mechanism, a second clutch for connecting 40 said closing mechanism to said second motor, a linkage extending from said shaft to said first clutch to cause engagement thereof upon partial depression of said foot-bar, and a second linkage including a lost motion connection 45 comprising a pair of rods extending past each other and a connecting dog normally permitting relative movement of said rods but binding the same together after partial depression of said foot-bar, said second linkage extending from said 50 shaft to said second clutch to cause engagement thereof upon continued depression of said foot-bar, said lost motion connection permitting engagement of said first clutch without engagement 55 of said second clutch whereby said conveyor may operate simultaneously with said sealing mechanism alone or simultaneously with both of said mechanisms.

ROBERT N. CUNDALL.
LINCOLN A. CUNDALL. 70
